PAPER MACHINE DISTRIBUTING APPARATUS

Jerome P. Strasser, Hampshire, Ill., assignor to
 Stein, Hall Manufacturing Company, Chicago,
 Ill., a corporation of Delaware

Application December 9, 1937, Serial No. 178,934

4 Claims. (Cl. 92—40)

This invention relates to paper making and more particularly to machines adapted to dispense materials onto the Fourdrinier wire of a paper making machine.

5 Successfully operating machines of this type are extremely difficult to construct owing to the varied uses to which they may be put. For example, if such a machine is installed in a paper making machine in conjunction with a Fourdrinier wire the task that it performs will depend upon the type of paper being manufactured at the time. Thus, during a certain run, the machine may be employed for the purpose of dispensing starch and starch compositions. However, it may be desirable on the next run to dispense a filler or another material and the machine has to be susceptible or capable of dispensing any such materials with complete success. Furthermore, it is contemplated that the machine may be employed for the purpose of delivering pulp to the Fourdrinier wire at the beginning of a paper making operation and this likewise is an additional task that requires the machine to be flexible and capable of almost universal use.

25 With the foregoing considerations in mind, an object of the present invention is the provision of a new and improved apparatus of the type described by which various materials may be applied on the paper machine during a paper making operation. Another object is to provide a machine which will apply these materials in such a way that the amount of material supplied is coordinated with the speed of the paper machine. Other objects and features of the invention will appear from a reading of the following specification in the light of the accompanying drawing in which

40 Figure 1 represents diagrammatically in side elevation the Fourdrinier wire of a paper making machine, including a diagrammatic representation of a distributing apparatus shown generally at A;

45 Figure 2 is a view in side elevation showing in detail the distributing apparatus illustrated generally at A in Figure 1;

Figure 3 is a plan view looking down on a portion of the distributing apparatus illustrated in Figure 2; and

50 Figure 4 is a diagrammatic view illustrating the manner in which the distributing apparatus may be employed to flow pulp onto the Fourdrinier.

The apparatus of this invention which has 55 proved successful on a commercial size paper

making machine consists generally of a vessel containing the material to be distributed, a drum or roll rotating in said vessel in contact with the material at its lower side, and an adjustable distributing blade adapted to remove excess material from the drum as it rotates and cause the material to flow uniformly and evenly down an inclined path toward the wire web of the machine, fins positioned within the path to collect and distribute the material, means for controlling the height and volume of the flow of material collected by the distributing blade, and means for controlling and varying the speed of the rotating drum or roll and the angle of inclination of the distributing blade adapted to control the volume of material dispensed and coordinate it with the speed of the wire.

5 By controlling the consistency of the composition to be added, the volume of flow admitted to the distributing blade, the angle of delivery 10 and the speed of the rotating drum or roll, it is possible to add to the wire just the right amount of material to obtain the desired characteristics. This construction is of outstanding importance. If the paper machine is speeded up the roll or 15 drum rotating in the dispersion may be likewise run at a faster rate and the angle of delivery 20 changed in order to maintain the proper proportion between the amount of material being added and the amount of material flowing across the 25 wire.

30 Referring to Figure 1, the diagrammatic drawing illustrates a conventional Fourdrinier paper making machine comprising the well known Fourdrinier wire or screen 2, which travels in the 35 usual way over a series of rolls designated as table rolls 4 in the shaker or vibrating portion of the machine, the suction couch roll 6, the dandy roll 8 and various other supporting rolls as generally illustrated. The wire or screen also 40 passes over suction boxes 10 which are of well known construction. The paper stock flows from the head box 12 onto the wire 2 and is carried by the wire at a relatively high rate of speed, usually varying anywhere from 125 feet per minute to 1000 feet per minute or more. At the point where the paper pulp flows on the wire the percentage of water is usually very high, ordinarily being 99% or more, and the remainder of the materials consists of pulp or fiber and various compounding ingredients added in the beater, as, for example, alum, various sizing agents, water proofing agents and other materials of a type well known in the industry. After 45 the stock passes along the wire a substantial portion 50 of the water is removed by the suction boxes 10 and the pulp is carried by the wire to the table rolls 4 where it is further treated. The pulp is then carried by the wire to the couch roll 6 where it is partially dried and then to the dandy roll 8 where it is 55 finally dried and made into a sheet of paper.

tion of the water is removed by gravity and another portion is removed at the suction boxes 10, so that the paper web when it has passed the couch roll 6 normally has its water content reduced to around 80%. Thereafter the wet sheet passes through the usual press rolls 14 and then into the customary drying apparatus which consists of numerous heated rolls over which the paper is passed in various ways until it is suitably dried.

The distributing apparatus generally illustrated at A of Figure 1, and more specifically illustrated in Figures 2 and 3, consists of a suitable container or box 16 which is mounted above the wire, preferably in the shaker or vibrating section of the paper machine. The box may be fastened to the frame of the paper machine if it is used on the stationary part of the Fourdrinier, or be supported independently, in such a way that it is stationary, if used on a moving or vibrating section. It is mounted upon any suitable type of adjustable mounting by which it may be raised or lowered, as, for instance, a screw device such as generally illustrated. The device shown for raising and lowering the box 16 consists of bolts 20 upon which are mounted nuts 22 and 24. A projecting portion 26 of the box is engaged by the nuts 22 and 24 and thus, by raising and lowering said nuts the box may be raised and lowered. Inside of the box 16 is a drum roll 28 which is driven by any suitable driving mechanism by means of which its speed may be controlled, so that any desired speed may be obtained that will provide the desired relationship with the varying speeds used on the paper machine. As roller 28 rotates, its lower portion picks up the solution or dispersion to be distributed and transfers at least a portion of said solution or dispersion to a spreader blade 30. Before said solution or dispersion is transferred to spreader blade 30, however, it passes beneath a doctor blade 32. This doctor blade 32 is positioned beyond the vertical axis through the center of rotating drum 28, as shown, and acts as a dam to control the height or level of the solution or dispersion on the rotating drum and to partially control the amount thereof taken off of the roll 28 by the spreader blade 30. The doctor blade 32 is adjustable as illustrated by means of threaded bolts 34 attached thereto and engaged with a frame 36 by means of nuts 38 and 40. The manner of raising and lowering the blade 32 by suitable adjustment of nuts 38 and 40 will be apparent from the detailed showing in the drawing.

The spreader blade 30 is held against roll 28 at a point 42 by means of a leverage device consisting of a spring 44 acting upon an arm 46 which is rigidly connected to the spreader blade 30. The tension on spring 44 may be increased or decreased by means of screw 48. As the tension is increased the arm 46 is depressed and spreader blade 30 is likewise depressed making and holding contact with rotating roll 28 at point 42.

Spreader blade 30 contains flutes or fins 50 near the lower end thereof which are preferably substantially rectangular in cross section. The top and bottom edges of fins 50 are preferably streamlined and of sufficient height to collect and distribute the dispersion or solution without allowing it to overflow from one flute or fin to the next. During a short space 52, after the dispersion or solution passes through fins or flutes 50, there is a plane surface over which the streams of starch dispersion flow and tend to merge into a

uniform unitary film of substantially the same height and volume throughout the width of the spreader blade. Thus, an even distribution of the dispersion on the paper web is insured. For the purpose of the invention the size of the flutes 5 or fins 50 and the distance therebetween may be varied according to the type and amount of material being delivered and according to the purpose for which the machine is to be used. For example, in delivering a dispersion of a starch 10 or filler to a machine in which the paper pulp is flowing at a rate of 500 to 600 feet per minute, the openings 54 may be about one-fourth inch wide and $\frac{1}{8}$ inch high, whereas in delivering a pulp or fibrous material, wider and higher flutes 15 may be necessary.

The height of the fluted blade 30 above the paper web may be controlled by means of an adjustable screw 56 or other suitable means. It will be observed that the blade 30 is supported 20 through a large portion of its surface by a truss or supporting element 58 which is connected to an arm 60. Arm 60 is an axis on which spreader blade 30 is adjusted in relationship to its contact with roll 28. Axis 64 is an axle which carries roll 25 28 and on which is mounted arm 60; it forms an axis for the movement and adjustment of spreader blade 30 in relation to its position at the paper machine wire. By adjustment of screw 56 arm 60 may be raised or lowered, thereby decreasing 30 or increasing the inclination of the spreader blade 30 with respect to the paper web flowing over the wire 2. The general relationship of the spreader blade 30 and rotating drum 28 is always substantially the same by virtue of the connect- 35 ing arm 60.

A dispersion to be distributed upon and into the paper web on the wire is introduced into the box 16 through any suitable opening such as illustrated at 66. By any suitable means (not shown) 40 a constant level or head of dispersion is maintained in box 16 through the introduction of the dispersion into the box at a rate greater than the rate of delivery. The roll 28 is preferably driven by a variable speed motor and the linear speed of 45 the roll corresponds to the linear speed of paper on the machine wire, although the linear speed of the roll may be slightly greater or slightly less than the rate of flow of the paper sheet. Good results have been obtained by having the rate 50 of flow of the dispersion, such as starch or starch compositions, over the blade 30, that is, the rate of delivery, slightly behind or lagging as compared with the rate of flow of the paper sheet. Thus, in a paper machine in which the paper is 55 being made at the rate of about 500 to 600 feet per minute the rate of flow of the starch dispersion onto the sheet from delivery blade 30 is preferably slightly less, say about 30 feet per minute less.

By regulating the concentration of the dispersion, the speed of the rotating drum or roll 28, the inclination of the spreader blade 30, the tension of the spreader blade 30 against the rotating drum 28 and the height of the doctor blade 32, 65 it is possible to regulate and control the rate and volume of dispersion and uniform distribution and to obtain a variety of desirable characteristics in the ultimate paper sheet without disturbing the formation thereof and without producing undesirable streaks or other undesirable characteristics as would necessarily be the case in previously proposed processes.

In carrying out the process with starch, the starch employed should be one which is dispers- 75

ible in water. Suitable starch dispersions may be prepared by methods known in the art.

It will be apparent that modifications may be made in the apparatus described without departing from the invention. For instance, the apparatus may be placed at points on the paper machine other than that shown in the drawing depending largely upon the characteristics desired in the paper produced. Thus, by mounting the apparatus in such a way as to deliver the material at the drier portions of the paper machine, it is possible to produce variations in the surface characteristics of the paper, but for most purposes where it is desired to improve the general characteristics of the paper and particularly the mullen and fold tests, excellent results are obtained by mounting the distributing device so as to deliver the dispersion to the paper web over the shaker portion of the machine.

Turning now to Figure 4, the distributing apparatus is shown in position to distribute pulp itself to the Fourdrinier wire. As thus illustrated, it takes the place of the customary head box and slice and has been found to be admirably adapted for the purpose at hand. For this operation, the distributing apparatus may be slightly modified. The fibrous material (e. g., a dispersion of $\frac{1}{4}\%$ to $\frac{1}{2}\%$ pulp in water with other customary ingredients) is supplied to the drum 68 from a suitable slotted pipe 70, or other means connected to a source of supply. As the fibrous material comes into contact with drum 68 it is carried forward and leveled to a suitable height and volume by a blade 72 or other suitable means for regulating the height and volume of the material. The material is taken from the drum by spreader blade 74 and distributed to the wire at the breast roll after passing through fins 76. A pan or trap 78 is provided to catch water flowing from drum 68. The entire apparatus may be made movable upwardly by jack screws 80 and to and from the paper machine by mounting on a track 82.

For some purposes, the fins in the spreader blade may be omitted, as, for instance, when the apparatus is used in making low grade papers. It is necessary at all times, however, to coordinate the rate of rotation of the drum, the angle of delivery of the spreader blade and the rate of flow of the material on the web of the paper machine.

This application may be considered a continuation-in-part of my copending application Serial No. 150,435, filed June 26, 1937.

Having thus described the invention, what I claim as new and desire to secure by Letters Patent of the United States is:

1. In combination with a Fourdrinier paper making machine, means for distributing material to a point on the wire of the paper machine, said means comprising a vessel containing the material to be distributed, means rotating in said vessel in contact with said material at its lower side, distributing means adapted to remove the material from the rotating means during rotation of the latter and cause said material to flow over said distributing means by gravity in an inclined

path toward the wire web of the paper machine, means for controlling the height and volume of the material on the rotating means comprising an elongated member extending lengthwise of the rotating means in a manner adapted to form a dam ahead of the distributing means, and means for coordinating the speed of the rotating means with the rate of flow of the wire web of the Fourdrinier machine.

2. In combination with a Fourdrinier paper making machine, means for distributing material to a point on the wire of the machine, said means comprising a vessel containing the material to be distributed, a drum rotating in said vessel in contact with the material at its lower side, a distributing blade adapted to remove the material from the drum during rotation of the latter and cause said material to flow over said blade by gravity in an inclined path toward the wire web of the paper machine, fins positioned in said blade to collect and distribute the flow of the material, means for controlling the height and volume of the material on the rotating drum comprising a doctor blade positioned lengthwise of the rotating drum in a manner adapted to form a dam ahead of the distributing blade, adjustable means for controlling the flow of the material over the distributing blade, and means for coordinating the speed of the drum with the rate of flow of the wire web over said paper making machine.

3. In combination with a paper making machine, means for distributing a material to a moving web on said machine, rotating means, means for supplying a material to be distributed to said rotating means, distributing means adapted to remove the material from the rotating means during rotation of the latter and cause said material to flow over said distributing means by gravity in an inclined path toward the web of the paper machine and means for controlling the height, volume and rate of distribution of the material distributed including means for adjusting and controlling the angle of inclination of the distributing means, means for controlling the height and volume of the material on the rotating means, and means for coordinating the speed of the rotating means with the rate of flow of the web of the paper machine.

4. In combination with a paper making machine, means for distributing a material to a moving web on said machine, rotating means, means for supplying a material to be distributed to said rotating means, distributing means adapted to remove the material from the rotating means during rotation of the latter and cause said material to flow over said distributing means by gravity in an inclined path toward the web of the paper machine and means for controlling the height, volume and rate of distribution of the material distributed including means for adjusting and controlling the angle of inclination of the distributing means, and means for coordinating the speed of the rotating means with the rate of flow of the web of the paper machine.

JEROME P. STRASSER.
